UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

BURNER.

1,285,936.

Specification of Letters Patent. Patented Nov. 26, 1918.

Application filed January 10, 1917. Serial No. 141,513.

To all whom it may concern:

Be it known that I, LEE S. CHADWICK, a citizen of the United States, residing at East Cleveland, in the county of Cuyahoga and State of Ohio, have invented a certain new and useful Improvement in Burners, of which the following is a full, clear, and exact description, reference being had to the accompanying drawings.

10 This invention relates to that class of hydrocarbon burners involving inner and outer commingling tubes between the lower ends of which the wick projects, and which are provided with perforations for admitting air to the combustion space between the tubes in such manner as to thoroughly commingle it with the gas generated at and rising from the wick, thereby to produce a readily combustible mixture.

15 It is well known to those familiar with burners of this character that the inner commingling tubes are much shorter lived than the outer ones. Employing terms of ordinary usage, the inner tubes are said to

20 "burn out" in a comparatively short time when subjected to usual service. The reason for this "burning out" of the inner tubes, while the outer tubes remain in good condition, is that the inner tubes become over-

25 heated for want of a sufficient supply of cool air. The outer tubes, on the other hand, are constantly subjected to the cooling influence of fresh air that is drawn upward into and through the drum.

30 The actual condition that is rather aptly expressed by the term "burned out" is an over carbonization of the metal whereof the inner tube is made and which comes about in this wise: The metal of the tube, when it reaches an extremely high temperature, acquires a chemical attraction or affinity for the carbon that is in the gas and proceeds to absorb or take on this carbon until after a comparatively short time it is 35 so overcharged with carbon that it becomes brittle and will actually crumble under its own weight. Note that it is only after the metal has reached an extremely high temperature that this action takes place to any appreciable degree. Therefore, to overcome this defect it is only necessary to prevent the inner commingling tube from attaining

so high a temperature, and it is the fundamental purpose of this invention to construct the inner commingling tube so as to accomplish this end. 55

In present constructions wherein the inner commingling tubes are provided with imperforate tops, the only outlet for the air rising within the tubes is through the perforations leading into the combustion space. Obviously this leaves a quantity or "core" of practically dead air to remain in the central part of the tube and beneath its top which becomes very highly heated, thus 60 overheating the tube. It is not unusual also for the products of combustion to be diverted inwardly through the perforations of the inner commingling tube by a down draft being created within the combustion space 65 by some external cause, and in that way establish a blaze within the tube which will rapidly raise the temperature of the tube to an extremely high degree.

The object of this invention, stated more 70 specifically than above, is the provision of an inner commingling tube having a top arrangement that will permit of or induce a current of air upward through the tube in excess of that required for the promotion of combustion within the combustion space, and to deflect such excess air toward the wall of the tube, thereby to modify the temperature of the tube, and so govern its discharge at the upper end of the tube as 75 to prevent its affecting the efficient action of the burner. Under the provisions of my invention, therefore, the inner tube is afforded practically the same favorable conditions 80 under which to operate as those above mentioned under which the outer tube exists; and by reason of this life of the burner is 85 greatly prolonged.

In the accompanying drawings I have 90 shown three constructions involving my invention and in any one of which the foregoing object is attained.

Figure 1 is a central vertical section through a burner embodying my invention, the lower portion of the wick tubes etc. being broken away; Fig. 2 is a fragmentary perspective view of the inner commingling tube shown in Fig. 1; Figs. 3 and 4 are views similar to Figs. 1 and 2 of a modifi-

cation of my invention; and Fig. 5 is a perspective view of the upper end of a further modified form of inner commingling tube, the same being shown as cut in section on its 5 vertical center.

In the drawings I have shown my improved commingling tubes associated with a common and well known style of burner, the same comprising an inner wick tube 1 10 and an outer wick tube 2 between which the wick 3 reposes and is adjustable by means of the usual wick raising mechanism; and within the upper end of the inner wick tube there is supported a deflector 4 which 15 compels the air rising through the tube to pass upward adjacent the wall thereof. The wick tubes 1 and 2 are provided adjacent their upper ends with commingling tube supporting ledges 5 and 6, respectively. Be- 20 cause of the general knowledge of the present burner, it is deemed unnecessary to show it in its entirety, it being understood that the space between the wick tube is supplied with liquid fuel through suitable means. I 25 may explain, however, that I do not limit the use of my improved commingling tubes to burners of this particular type but consider that they may be employed with any burner adapted for use with commingling 30 tubes.

The inner commingling tube 10 is adapted to rest upon the ledge 5 and is provided substantially from top to bottom with perforations 11, the lowermost row of perforations 35 being deprived of communication with the space inside the tube by the vertical wall 12 of a diaphragm 13 which extends across the lower end of the tube, the wall 12 having its upper edge turned outward and then 40 upward to provide a peripheral flange 14 which is secured by suitable means to the tube. The body portion of the diaphragm 13 has perforations 15, and a thimble 16 is connected to the elevated central portion of 45 the diaphragm by having its lower end reduced and passed through a central aperture of the diaphragm and upset on the underneath side thereof. The socket 17 of the thimble receives the upper end of the lifter-rod 18 whereby the commingling tubes 50 may be elevated from the ledges of the wick tube when it is desired to light the burner. The lifter-rod is a feature common to many burners that are now on the market and further showing or description of it is thought 55 to be unnecessary.

Lugs 20 are struck inward from the wall of the tube 10 a slight distance below its upper end, and these lugs support the depending peripheral flanges of a disk or deflector 21 and a hood 22, the latter being shown as of frusto-conical formation and provided with a central aperture 23. The edges of the hood and disk or deflector are 60 held together and in contact with the lugs 65

20 by the inturned upper edge of the tube. The disk or deflector 21 is provided with a series of openings 25 near its edge.

An outer commingling tube 28, having 70 perforations 29, is adapted to rest upon the ledge 6 of the outer wick tube and is maintained in substantially concentric relation to the inner tube by means of cross rods 30 which are arranged at right angles to each other and pass through the walls of the two 75 tubes. The openings of the inner tube through which the rods pass are elongated vertically so as to allow a slight vertical movement between the two tubes for the purpose of permitting them to adjust themselves to any slight irregularities in their supporting ledges or to compensate for any foreign matter which may be upon the ledges and interfere with their seating.

The rods 30 extend beyond the outer commingling tube and support in proper relation to such tube a drum 32 having an annular bottom wall 33 which extends inward and upward adjacent the lower end of the outer commingling tube and is provided 80 with perforations 34. The rods 30 are held against withdrawal from the drum and tubes by a head at one end and a cotter pin 31 which extends through the other. An annular top wall 35 is also provided for the 85 drum which extends upward and inward from its upper end and terminates above the upper end of the outer commingling tube. The drum is equipped with a handle 37.

In the operation of the burner, gas is 100 generated about the upper end of the wick and rises within the combustion space between the commingling tubes. It is supplied with the required oxygen through the perforations of the commingling tubes, the 105 gas receiving its first supply of oxygen in the air which is drawn inward through the lowest row of perforations in the inner commingling tube and that which is drawn inward through the opposite row of perforations of the outer tube. By reason of the 110 peculiar edge formation of the diaphragm 13, a sufficient initial supply of air is insured. The wall 12 deflects a quantity of the air that sweeps upward about the deflector 4 and compels it to pass through the bottom row of perforations of the inner commingling tube. As the gas ascends within the combustion space it continues to receive oxygen from the air that is drawn inward through the perforations of the inner and outer commingling tubes. The air which passes through the perforations of the outer commingling tube is supplied through the space between the lower end 115 of the said tube and the inner upturned edge of the bottom wall 33 of the drum, and also through the perforations 34 of said wall. However, the quantity of air thus supplied to the space within the drum is 120 125 130

considerably in excess of that required for the promotion of combustion, and this excess air has the effect of maintaining the temperature of the outer commingling tube 5 at a comparatively low degree.

Likewise, with respect to the inner commingling tube, the quantity of air which is admitted to the interior of the tube through the perforations 15 of the diaphragm 13 is 10 greater than is required to promote combustion, and consequently this air rises as rapidly as the conditions dictate to the upper end of the tube where it escapes through the openings 25 in the disk 21 and the aperture 15 23 of the hood 22. The openings 25 being located as they are adjacent the periphery of the disk causes the disk to act as a deflector in compelling the air to pass in proximity to the wall of the tube, thus having a 20 greater cooling effect thereon than it would have if it were allowed to rise directly through the tube. However, beyond the disk 21, it is essential that the discharge of air be restricted substantially to the center 25 of the burner in order to keep it from disturbing the draft upward through the combustion space. This end is accomplished through the formation of the hood 22, and location of the aperture thereof.

30 The construction shown in Figs. 3 and 4 is identical with that shown in Figs. 1 and 2, with the exception of the disk and hood. Therefore I shall employ the same reference numerals in designating the corresponding 35 parts of the two constructions. The disk and hood, which are of modified form, will have applied to them the same numerals as in the former case, augmented by the exponent *a*.

40 In Figs. 3 and 4 I have shown the disk or deflector 21^a perforated substantially throughout its area, but it will be observed that the same is more foraminous toward its periphery than in the vicinity of its center, 45 which will have the effect of maintaining the greater draft of air upward adjacent the wall of the tube. In the present case I have also shown the hood 22^a as being perforated quite freely outward from the center to its 50 edge, but it will be noted that the perforations increase in size inward from the edge. Therefore, practically the same effect is attained in this construction as in the one previously described.

55 Fig. 5 shows a construction wherein the hood 22^b is provided with a single centrally located aperture 23^b, and the disk or deflector 21^b is supported within the upper end of the inner commingling tube with its edge 60 spaced a substantially equal distance from the tube throughout its circumference by studs 40 which have their upper and lower ends reduced and passed through the top wall of the hood and the disk, respectively, 65 and upset therebeyond.

It will be seen upon reflection that the purpose and principle of operation are the same in all forms of my invention herein disclosed; but it will be appreciated at the same time that the object of maintaining the draft 70 adjacent the wall of the inner commingling tube and centralizing its discharge therefrom is attained with greater certainty in the forms shown in Figs. 1, 2 and 5 than in the modification displayed in Figs. 3 and 4. 75

In the above description of the operation of the burner, I have brought out one effect which the upturned imperforate edge portion 12 of the diaphragm 13 has upon the action of the burner, to wit, that of assuring a sufficient supply of air to the lower portion of the combustion space to properly promote combustion by deflecting a quantity of the air rising about the deflector 4 outward through the lowest row of perforations of the inner commingling tube. In this connection it will be well to explain that the velocity with which the air rises through the inner commingling tube permits only enough air to pass through the 80 perforations 11 thereof above the diaphragm to produce a comparatively small and unsteady flame at each perforation. This assists in preventing an overheating of the inner commingling tube. 95

It has already been explained how, in prevailing types of burners, a down draft created within the combustion space by some external cause has the effect of diverting the gas and products of combustion inward 100 through the perforations of the inner commingling tube and of establishing a blaze therewithin. Obviously this reversal of conditions has its start in the lower portion of the commingling space where the products are backed up and have to find their escape through the perforations of the commingling tubes. 105

Now, bearing the above in mind, another effect which the imperforate edge portion 110 12 of the diaphragm has is that of preventing the products of combustion from reaching the interior of the inner commingling tube upon the instance of a down draft in the combustion space, and the resultant deflection of the flame through the lowest 115 row of perforations because of the immediate proximity of this row to the flame. Under such conditions, the products, after passing through said lowest row of perforations 120 are directed downward by the edge portion 12 of the diaphragm into the fresher air therebeneath and are hastily extinguished. Without the imperforate edge portion 12 extending above the lowest row of perforations, it would be possible for a reverse fire 125 to be started at the lowest row of perforations and consequently continued all the way up the tube.

Again, under normal operation of the 130

burner, the edge portion 12 insures a steady current of air through the lowest row of perforations, thereby initiating a proper draft within the lower portion of the combustion space, and this, in turn, tends to maintain a proper draft thereabove and to promptly readjust any drafts of the higher perforations that might have been diverted.

Having thus described my invention, what

10 I claim is:—

1. In a burner of the character set forth, the combination of an inner and an outer perforated commingling tube between the lower ends of which a wick is adapted to be projected, the inner commingling tube having an open top, and a deflector within the tube for directing the air passing upward through the tube and out of the open top thereof into close proximity to the wall of 20 the tube.

2. In a burner of the character set forth, the combination of an inner and an outer perforated commingling tube between the lower ends of which a wick is adapted to be projected, and a plate extending across the upper end of the inner commingling tube and having perforations decreasing in size from the periphery toward the central portion thereof.

3. In a burner of the character set forth, the combination of an inner and an outer perforated commingling tube between the lower ends of which a wick is adapted to be projected, a plate extending across the upper end of the inner commingling tube and having perforations adjacent its edge, and a hood surmounting said tube and having a central discharge opening.

4. In a burner of the character set forth, 40 the combination of an inner and an outer perforated commingling tube between the lower ends of which a wick is adapted to be projected, a perforated plate extending across the upper end of the inner commingling tube, and a hood surmounting said tube and having perforations which decrease in size from its center toward its edge.

5. In a burner of the character set forth, 50 the combination of an inner and an outer perforated commingling tube between the lower ends of which a wick is adapted to be

projected, the inner commingling tube having a horizontal row of perforations spaced a comparatively short distance above its lower edge, and a diaphragm extending across the 55 lower end of said tube and having its body portion perforated and its edge portion turned upward along the wall of the tube and then outward into contact therewith above said row of perforations.

6. In a burner of the character set forth, the combination of an inner and an outer perforated commingling tube between the lower ends of which a wick is adapted to be projected, the inner commingling tube having a horizontal row of perforations spaced a comparatively short distance above its lower edge, and a diaphragm extending across the 65 lower end of said tube and having its body portion perforated while its edge portion is imperforate and is turned upward along and spaced from the wall of the tube and is then turned outward into contact with said wall above said row of perforations.

7. In a burner of the character set forth, 75 the combination of an inner and an outer perforated commingling tube between the lower ends of which a wick is adapted to be projected, the inner commingling tube having a horizontal row of perforations spaced 80 upward a comparatively short distance from its lower end, and having also a top that is provided with an opening, and a deflector extending inward and downward from the wall of the tube immediately above said row 85 of perforations.

8. In a burner of the character set forth, the combination of an inner and an outer perforated commingling tube between the lower ends of which a wick is adapted to be 90 projected, and a plate extending across the upper end of the inner commingling tube and having perforations extending from the vicinity of its periphery toward the central portion thereof, the aggregate area of 95 such perforations decreasing inwardly.

In testimony whereof, I hereunto affix my signature in the presence of two witnesses.

LEE S. CHADWICK.
